TRIMMING MACHINE

Clyde L. Knott, Beverly, Mass., assignor to United Shoe Machinery Corporation, Flemington, N. J., a corporation of New Jersey

Application July 29, 1943, Serial No. 496,544

9 Claims. (Cl. 12—83.5)

This invention relates to trimming machines and is herein illustrated and described as embodied in a machine suitable for trimming the excess material from the overlasted marginal portion of the upper in the manufacture of a cement lasted shoe. It is necessary in such trimming operations to break the cement bond which binds the upper to the insole and to raise the portion to be trimmed from the insole. It is also desirable, in order to assure uniform trimming, to raise the marginal portion of the upper at a fixed distance inwardly from the perimeter of the shoe bottom.

It is an object of the present invention to provide a trimming machine capable of operating in the manner outlined above. In accordance with a feature of the invention the illustrated machine is provided with a gage engageable with the overlasted margin of the upper and having a shoulder about which the upper material may be bent away from the shoe bottom by a lifting tool, a gage engageable with the perimeter of the shoe bottom, and trimming means adjacent to the first mentioned gage. The lifting tool, shown herein, has a wedge-shaped nose which enters between the insole and the margin of the upper and which is moved in an orbital path which is relatively flat in the vicinity of the shoe bottom to enable the tool to advance in contact with the insole and which then curves to cause the tool to raise the loosened margin and to be retracted out of contact with the shoe bottom. The flatness of the orbital path in the vicinity of the shoe bottom is important in enabling the tool to pick up the margin of the upper material regardless of variations of distance of the edge of the upper material inwardly from the perimeter of the shoe bottom. The trimming means consists of a knife mounted for movement about a fixed axis, the blade of the knife being curved about the same axis. If desired, the knife may be circular in form and it may be continuously rotated. However, in the illustrated machine, the knife is oscillated about its axis of rotation, and it is arcuate rather than circular. The oscillation of the knife is effected by a link from the same mechanism which operates the lifting tool, and in such a manner that while the tool is advancing the knife moves in a direction opposite to that of the tool and while the tool is being retracted the knife moves in a direction tending frictionally to raise the margin of the upper material.

With the above and other objects and features in view the invention will now be described in connection with the accompanying drawings and will be pointed out in the claims.

Referring to the drawings,

Fig. 1 is a front elevation of the upper portion of an illustrative machine;

Fig. 2 is an enlarged view of the front elevation showing the operating instrumentalities of the machine in relation to a shoe;

Fig. 3 is a view in perspective of the forward portion of the shoe illustrating the character of the operation performed by the machine.

Fig. 4 is a plan view, partly in section, of the operating instrumentalities;

Fig. 5 is a view in front elevation, partly in section, on a scale still larger than that of Fig. 2; and

Fig. 6 is a side elevation, partly on a section taken on the line VI—VI of Fig. 2, of the parts shown in Fig. 5.

In the description which is to follow the term "shoe" is used to denote the assembly of a lasted upper and insole; and the term "shoe bottom" to denote the exposed surfaces of the insole and of the over-lasting margin of the upper.

The operating instrumentalities of the illustrated machine comprise a tool 10 in the form of a finger having a wedge-shaped nose 38 (Fig. 5) for raising a portion of the overlasted margin of the upper U of a lasted shoe S, an arcuate knife 12 for trimming the raised portion of the upper, and a bracket 14 which carries facilities for gaging the shoe relatively to the tool 10 and the knife 12. These various members are all supported by a frame 16 (Fig. 1) adapted to rest upon the floor and having a laterally extending upper portion 18 which is integral with the remainder of the frame. If desired, the frame 16 may be designed to be secured to a work bench.

Journaled in suitable bearings carried by the frame 16 is a shaft 20 which may be driven by any suitable source of power. Secured upon the shaft 20 is an eccentric 22 upon which is mounted one end of an eccentric rod 24. The rod 24 at a locality adjacent to its opposite end is pivotally connected by a pin 25 to a supporting link 26 which extends downwardly. The lower end of the link 26 is pivotally mounted for free swinging movement upon a pin 28 secured in the frame member 18. The end portion of the rod 24 beyond the link 26 carries a block 30 which is adjustable in a direction parallel to the axis of the shaft 20. Provision for such adjustment is obtained by means of a guideway 32 formed in the rod 24 and along which the block 30 is slidable.

The block 30 may be clamped in any desired position of adjustment along the guideway 32 by a bolt 34 threaded into the rod 24 and extending

through a slot in the block 30. The block 30 has formed in it a guideway for the tool 10. The block is split along the guideway to enable the tool 10 to be secured by a clamping bolt 36 with the point or nose 38 of the tool 10 (Fig. 5) in any desired position or adjustment along a line which lies in a plane normal or radial to the axis of the shaft 20. It will be noted that by reason of the fact that the supporting link 26 extends downwardly from the rod 24 to a fixed supporting pivot pin 28 the path of the nose 38 of the tool 10 will be ellipsoidal in form as indicated by the closed curve (broken line, Fig. 5) 40 and that the lower portion of this path is relatively flat as compared with the bulging upper portion.

The bracket 14 has a shank 41 which extends upwardly with a slight inward inclination, and which is slidably mounted for heightwise adjustment upon the frame member 18 and may be secured thereon in any desired position of heightwise adjustment by a clamping bolt 42 extending through a slot 44 in the shank 41 and threaded into the frame member 18. Carried by the shank 41 and extending outwardly therefrom (i. e., in a direction away from the shaft 20) and also rearwardly therefrom in a direction parallel to the shaft 20 is a flange or foot 45. The major portion of the under surface of the foot 45 (indicated in Fig. 1 by the numeral 46) is plane and parallel to the axis of the shaft 20, being a little above the level of the axis of the shaft 20, and sloping downwardly at a slight angle to the horizontal in a direction away from said axis. This under surface 46 serves as a height gage against which the shoe is held inverted with the overlasted margin U in contact therewith. Mounted for free rotation upon a pin 48 secured in the foot 45 is a roll 50 adapted to bear against the perimeter of the shoe bottom, which roll constitutes a stop or an abutment to determine the lateral position of the shoe. The pin 48 extends through a slot 49 (Fig. 4) in the foot 45, and may be secured in said slot in any desired position of adjustment toward or away from the shaft 20 by a nut 51. The gaging surface 46 terminates abruptly in an obtuse angle at the elbow of the shank 41 to form a straight edge or shoulder 56 (Figs. 1 and 4). From the shoulder 56 the inner surface of the shank 41 slopes upwardly and inwardly at a slight angle from the vertical. The shoulder 56 continues rearwardly beyond the shank 41, constituting the lower and inner (or righthand) edge of the foot 45, and the edge surface of the foot is continuous with the inner surface of the shank 41, sloping upwardly and inwardly at the same slight angle from the vertical to an edge 57 only slightly above the shoulder 56. Above the edge 57 the edge surface of the foot is beveled upwardly and outwardly, as indicated by the reference character 59 on Figs. 4 and 5. The foot 45 extends rearwardly nearly to the cutting edge of the knife 12, and it has a lug 61 which extends rearwardly over the cutting edge of the knife, the under surface of the lug being beveled upwardly (to the line 63 on Fig. 5) from the gaging surface 46 in the form of a frustum of a cone co-axial with the knife in the extreme right-hand position of adjustment of the knife to enable the lug 61 to clear the knife. The continuation of the shoulder 56 along the lug 61 and over the knife serves as a shearing edge for holding the work against the knife 12. This shearing edge, which slopes upwardly and rear-

wardly relatively to the shoulder 56, is indicated on Fig. 4 by the reference numeral 67.

Rotatably mounted for oscillation upon a pin 58 secured in the shank 41 is a sector 60 having an arm 62 extending upwardly and inwardly, or toward the right, as shown in Figs. 1 and 2. The upper end of the arm 62 is pivotally connected to one end of a link 64, the opposite end of which link is pivotally mounted on the pin 25. The sector 60 has a web in which is formed an opening 65 (Fig. 5) through which the severed upper stock may pass. The sector 60 also has a peripheral flange or rim 66 (Fig. 6) which is frusto-conical in shape. Clamped against the outer surface of the rim 66 by an arcuate clamping plate 68 is the knife 12, which is flexible. A portion of the forward edge of the clamping plate is beveled for clearance, as indicated by the reference numeral 69 in Figs. 4 and 6. A pair of radial clamping screws 72 threaded into the sector 60 hold the arcuate plate 68 in clamping position. It will be observed that the oscillation of the pin 25 about the pin 28 will be transmitted through the link 64 to rock the sector 60 about the fulcrum pin 58 and thereby to operate the knife.

The knife 12 may be adjusted heightwise with respect to a sole held against the gaging surface 46. Such adjustment is made possible by an arrangement wherein the pin 58, upon which the knife sector is mounted, extends through a slot 74 formed in a boss 76 on the shank 41. The slot 74 is arcuate about an axis which coincides with an extension of the straight line defining the edge 56 of the gaging surface 46. One end of the pin 58 has a head 78 which bears against one end of a spacing collar 80 interposed between the pin 58 and the hub of the knife sector. The other end of the collar 80 bears against a washer 81 which engages a finished surface on the boss 76. The opposite end of the pin 58 has threaded thereon a nut 82 which holds a washer 84 against the boss 76. The pin 58 may thus be clamped in any desired position of adjustment in the slot 74, and the hub of the knife sector is freely rotatable about the collar 80 for any such position of adjustment. The radius of the knife 12 about the axis of the pin 58, and the radial distance of the axis of the pin 58 from the edge 56, are made exactly equal to insure the cutting edge of the knife 12 always, regardless of the adjustment of the pin 58 in the slot 74, passing through the line (extended) which defines the edge 56.

As shown in Fig. 6, the tool 10 is positioned rearwardly of the shank 41 and forwardly of the knife 12. The bracket 14 thus serves as a guard for the tool and the knife.

In operating the machine, the attendant holds the shoe S in the position shown in Fig. 2 with the overlasted portion of the upper U in contact with the gaging surface 46, and with the perimeter of the shoe bottom (indicated by the reference character P in Figs. 3 and 6) substantially in engagement with the roll 50. The roll 50 should first be adjusted along the arm 45 to bring the shoulder 56 to a desired position inwardly from the perimeter of the shoe bottom. The purpose of the tool 10 is first to break the cement bond between the overlasted margin of the upper U and the insole (identified by the reference character I), and second to raise this marginal portion by bending it upwardly around the shoulder 56. The tool 10 is accordingly adjusted longitudinally in the block 30 to bring the

wedge-shaped nose of the tool relatively close, allowing for the thickness of the upper material, to the shoulder 56 when the tool is in its most advanced position. The nose 38 of the tool, moving clockwise in an ellipsoidal path 40 (Fig. 5) will enter between the edge of the overlasted margin of the upper and the insole and advance along a relatively flat curve which is substantially tangent to the surface of the insole, breaking the cement bond between the upper material and the insole. The bracket 14 should be adjusted heightwise to insure this condition of substantial tangency. As the advancing movement of the nose of the tool continues the tool will rise from the insole and bend the freed upper material about the shoulder 56 and away from the insole to form a flap F. The arcuate knife 12 is positioned under the beveled undersurface of the lug 61 to sever the flap F. The pin 58 should be adjusted in the slot 74 to bring the cutting edge of the knife 12 substantially tangent, allowing for reasonable clearance, to the insole. This condition is shown in Fig. 5 wherein the arc K represents the cutting edge of the knife. If the upper material were thicker, the pin 58 would have to be adjusted further to the right and the cutting edge of the knife would then assume a lower position, for example, such as that represented by the arc K' (in broken lines). It will be observed that both arcs pass through the line representing the shoulder 56, extended. As shown in Fig. 5, the knife makes a scarf cut. It is important that the lower or inner edge of this scarf should substantially coincide with the line along which the cement bond between the upper material and the insole has been broken. The above-mentioned heightwise adjustment of the knife for different thicknesses of upper stock satisfies this condition, and results in a neater and cleaner scarf than could be obtained otherwise. During the advancing of the tool 10 the knife will be moved by the link 64 in a counter-clockwise direction about the axis of the pin 58, and whatever frictional drag the knife may exert upon the upturned margin of the upper will be resisted by the advancing tool 10. The operator all the while is feeding the shoe to the left, as viewed in Fig. 6, in contact with the roll 50 and the gage surface 46 to bring fresh portions of the upturned flap into engagement with the knife and to bring fresh portions of the cemented margin of the upper into engagement with the lifting tool 10. While the lifting tool 10 is being retracted and is out of contact with the flap F, the knife 12 will be moving in a clockwise direction and will, therefore, tend by reason of its frictional drag to hold the flap against the shoulder 56. Fig. 3 shows the forepart of a shoe that has been removed from the machine, for purposes of illustration, before completion of the operation. The overlasted margin of the upper U has been trimmed along a line L parallel to the perimeter P of the shoe bottom.

Having thus described my invention what I claim as new and desire to secure by Letters Patent of the United States is:

1. An upper-trimming machine comprising a gage engageable with the overlasted margin of the upper of a shoe and having a shoulder about which the portion of the overlasted margin adjacent to the edge of the upper may be bent away from the shoe bottom, a gage engageable with the perimeter of the shoe bottom to insure a predetermined distance between said shoulder and the perimeter of the shoe bottom, a tool for rais-

ing said portion of the overlasted margin of the upper and bending it over said shoulder, and means adjacent to the first-mentioned gage for trimming the raised portion of the overlasted margin of the upper.

2. An upper-trimming machine comprising a work-guiding member having a shoulder arranged to be engaged by the overlasted margin of the upper material lying on the insole of a lasted shoe, an abutment spaced from said shoulder and arranged to be engaged by the perimeter of the shoe bottom, a wedge-nosed tool arranged to be inserted between the insole and the edge of said margin, power-operated means for moving the nose of said tool in an ellipsoidal path to bend surplus material of said margin over said shoulder, and power-operated cutting means arranged to sever the surplus material so bent.

3. An upper-trimming machine comprising a power-driven knife, a guard located in front of the knife to be engaged by the overlasted margin of the upper material lying on the insole of a lasted shoe, an abutment arranged to be engaged by the perimeter of the sole of the shoe, said guard having an edge spaced from said abutment inwardly of the perimeter of the sole, a finger having a tip engageable with the insole and the surplus overlasted upper material projecting inwardly beyond the edge of said guard, and power-driven means for moving said finger toward and from said abutment, said finger having an inclined face arranged to run under said surplus material and bend it on said edge away from the insole and in a position to be cut by said knife.

4. An upper-trimming machine comprising a tool having a wedge-shaped nose adapted to be inserted between the insole of a lasted shoe and the overlasted margin of upper material lying on the insole, a work-guiding member having a bearing surface arranged to be engaged by said margin and along which the shoe may be advanced, an abutment arranged to be engaged by the perimeter of the shoe bottom, and a power-operated knife having an arcuate cutting edge and movable about the axis of said edge to execute a draw cut, said tool being constructed and arranged to bend the surplus marginal material of the upper about said work-guiding member in a position to be cut by said knife as the shoe is advanced.

5. An upper-trimming machine comprising a gage engageable with the overlasted margin of the upper of a shoe and having a shoulder about which the portion of the overlasted margin adjacent to the edge of the upper may be bent away from the shoe bottom, a guide for the perimeter of the bottom of the shoe as the shoe is fed in contact with said gage, a wedge-nosed tool adapted to enter between the edge portion of the overlasted upper and the insole to raise the upper material from the insole, an arm upon one end of which said tool is mounted, means for moving the other end of said arm in a circular path, a link having one end pivotally connected to said arm, a pivotal mounting for the other end of said link about which the link may swing to constrain the movement of said tool to a closed path in a portion of which the tool advances in operative contact with the work and in another portion of which the tool is retracted out of contact with the work, a lever, a fulcrum upon which said lever is pivotally mounted, a knife carried by said lever and arranged to sever the upper material raised by said tool, said knife having

a curved blade coaxial with said fulcrum, and a link pivotally connected at one end to said lever and at the other end to the first-mentioned link for rocking said lever to oscillate the knife, the second-mentioned link being arranged to move the knife in a direction tending frictionally to raise the margin of the upper while the tool is being retracted.

6. A device for raising the margins of cement-lasted uppers, comprising a gage having an undersurface engageable with the bottom of an inverted cement-lasted shoe to determine the heightwise position of the shoe, a wedge-nosed tool adapted to enter between the edge portion of the overlasted upper of the shoe and the insole, an arm upon one end of which said tool is mounted, means for moving the other end of said arm in a circular path, a link having one end pivotally connected to said arm between said tool and said moving means and extending downwardly, and a pivotal support for the other end of the link for confining to an arcuate path the movement of that portion of the arm to which the link is pivotally connected, whereby the nose of the tool will be constrained to movement in a closed path which is relatively flat in the vicinity of the bottom of a shoe held against said gage.

7. In an upper-trimming machine, a tool for raising a portion of the overlasted margin of a shoe upper from the insole, means for driving said tool in a predetermined path, gaging means for determining the position of the shoe both heightwise and laterally with respect to the path of said tool, a knife for trimming the portion of the upper which has been raised by said tool, and a support for said knife constructed and arranged for heightwise adjustment with respect to said gage to adapt the machine for operation upon shoes having different thicknesses of upper material.

8. In an upper-trimming machine, a tool for raising a portion of the overlasted margin of a shoe upper from the insole, means for driving said tool in a predetermined path, a bracket having a gaging surface engageable with the overlasted margin of the shoe upper, a support upon which said bracket is mounted for heightwise adjustment to determine the heightwise position of the shoe relatively to the path of said tool
- 5 10 when the overlasted margin of the upper is held against said gaging surface, a knife on said bracket for trimming the upper material which has been raised by said tool, and an adjustable connection between said knife and said bracket
- 15 for enabling the knife to be secured to the bracket in various positions of heightwise adjustment to accommodate different thicknesses of upper material.
9. In an upper-trimming machine, a trimming knife mounted for movement about an axis and having a cutting edge of which all portions are equidistant from said axis, a gage engageable with the overlasted margin of the upper of a shoe to determine the heightwise position of the shoe relatively to the knife, a member having a shoulder in the form of a straight edge about which the upper material may be bent away from the insole, and a support for said knife constructed and arranged for adjustment to vary the position of the axis of the knife over an arc, the axis of which arc is an extension of said straight edge, the radius of the cutting edge of the knife being equal to the radius of said arc
- 20 25 whereby the cutting edge of the knife will pass through the axis of the arc for all positions of adjustment of the knife, and the purpose of said adjustment being to adapt the machine for operation upon shoes having upper material of different thicknesses.
- 30 35 40 CLYDE L. KNOTT.
